[57] CLAIM

The ornamental design for a fulcrumed tool for a shovel or similar article, as shown and described.

DESCRIPTION

FIG. 1 is a perspective view of a fulcrumed tool for a shovel or similar article, showing my new design;

FIG. 2 is a left side elevational view, the right side being substantially a mirror image thereof except for the securing of the handle portion to the base plate and the diagonally affixed stirrup, as shown in FIGS. 1, 3-5;

FIG. 3 is a front elevational view thereof;

FIG. 4 is a top plan view thereof; and

FIG. 5 is a bottom plan view thereof.

FIG. 1

FIG. 5

FIG. 2

FIG. 3

FIG. 4
